UNITED STATES PATENT OFFICE.

ALBERT FARR, OF ATHOL, MASSACHUSETTS.

CRUTCH.

SPECIFICATION forming part of Letters Patent No. 242,618, dated June 7, 1881.

Application filed March 26, 1881. (No model.)

To all whom it may concern:

Be it known that I, ALBERT FARR, of Athol, in the county of Worcester and State of Massachusetts, have invented certain new and useful Improvements in Crutches for Invalids; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to certain improvements in crutches.

15 It consists of a crutch having a spur connected by a rod to the hand-hold, which is journaled or pivoted in the bows of said crutch, said spur being capable of a movement down or up under the influence of the hand, by a movement of said hand-hold about its axis.

In my drawings, Figure 1 is an elevation of the crutch. Fig. 2 is a section of same. Fig. 3 is a sectional view, showing a modification of the packing at the foot of the crutch.

25 Similar reference-letters indicate like parts in all of the figures.

Referring to drawings, A is the crutch, having its upright split or divided a part of its length, forming bows A'. Between said bows, at a convenient point, is secured a hand-hold, B, provided with tenons a a, adapted to fit into mortises c c. The hand-hold B is secured to said bows A' by screws f f, which enter the bows and said hand-hold from opposite sides, forming the axis of motion to the spur.

A cross-piece, D, fashioned to suit the arm-pit of a person, unites the bows A' in the usual manner.

40 A bifurcated lug, e, is secured to the periphery of the hand-hold B radially from its axis, and to said lug is pivoted a rod, E, which passes down through the lower part and foot of the crutch by way of an opening provided for it.

45 The foot of the crutch is protected by a ferrule, F, provided with an annular flange, g, which extends inward and incloses between it the wooden end of the crutch and the rod E, a piece of rubber, leather, or other suitable

50 packing material, h, elastic in its nature, which is intended to impinge closely upon said rod

or spur at all times, to prevent gravel, sand, or water, which is liable to freeze in cold weather, from entering the opening through which said rod passes to interfere with a free and easy movement of the spur in or out.

The ferrule F is secured to the foot of the crutch by rivets, nails, or anything in common use to answer the purpose.

The operation of the spur of my crutch is as follows: The person using the crutch, when in position, has his arm resting in the arm-bearing or cushion and his hand grasping the hand-hold B. When he desires to throw out the spur he has only to revolve said hand-hold a few degrees to bring the rod E in the axial line of the crutch. When in this position there will be no liability of the spur to recoil, as said hand-hold will form a solid abutment to prevent a movement of the rod upward. A second movement of the hand-hold, either to the right or left, will release the spur and withdraw it within the foot of the crutch.

In the modification shown in Fig. 3 the piece of rubber or elastic packing material h, extending outside of the ferrule, serves the double purpose of packing for the spur and a cushion to form a noiseless friction-tread. The purpose of this will be appreciated when we consider that it is frequently the case that it would be best not to use the spur—as, for instance, when passing over slippery surfaces impenetrable to pointed metal. Under such circumstances the spur might be withdrawn, to allow the packing or cushion to bear directly upon such surface without impediment.

In speaking of the operation of my device I have described the spur, when out of service, as being in the axial line of the crutch, and the importance of this position at times is obvious; but I do not consider this to be essential at all times when said spur is in use.

In some cases, as when passing over wooden or like surfaces, I would prefer that the point should take but a slight hold, and in such a case the movement of the hand-hold would be in a small arc, to give but slight motion to rod E, it being held firmly and controlled by the operator when so moved.

I am aware that crutches have been made wherein rods with spurs have been used and operated by the hand to withdraw said spur

by a lifting movement in a direct or axial line, and to such I make no claim.

I am also aware that an elastic material has been used, fixed in a socket at the end of 5 a crutch to prevent slipping, and to such, broadly, I make no claim; neither do I set up any claim for a spur attached to a rod provided with screw-threads by which it may be adjusted in a correspondingly screw-threaded 10 substance in its axial line to protrude said spur to any degree required, as this is not my invention.

Having thus described my invention, what I claim as new, and desire to secure by Letters 15 Patent, is—

The herein-described crutch, provided with a hand-hold adapted to rotate in the bows of said crutch, in combination with a rod hinged to said hand-hold, and provided with a spur which protrudes from the foot of said crutch, 20 as and for the purpose set forth.

In testimony that I claim the foregoing as my own I affix my signature in presence of two witnesses.

ALBERT FARR.
